(57) **CLAIM**

The ornamental design for a hanging dispenser, as shown and described.

DESCRIPTION

FIG. 1 is a top front perspective view of a hanging dispenser, showing our new design.

FIG. 2 is a bottom rear perspective view of the hanging dispenser.

FIG. 3 is a front elevational view of the hanging dispenser.

FIG. 4 is a rear elevational view of the hanging dispenser.

FIG. 5 is a left side elevational view of the hanging dispenser.

FIG. 6 is a right side elevational view of the hanging dispenser.

FIG. 7 is a top plan view of the hanging dispenser; and, FIG. 8 is a bottom plan view of the hanging dispenser.

The hanging dispenser is shown with symbolic breaks in its length and width. The appearance of any portion of the article between the break lines forms no part of the claimed design. Features illustrated in broken lines are for the purpose of showing environmental structure that forms no part of the claimed design.
